B. SCHMITH

CIRCUIT CLOSING DEVICE FOR AUTOMOBILES

Filed August 8, 1923

Patented June 1, 1926.

1,587,489

UNITED STATES PATENT OFFICE.

BALDINI SCHMITH, OF PHILADELPHIA, PENNSYLVANIA.

CIRCUIT-CLOSING DEVICE FOR AUTOMOBILES.

Application filed August 8, 1923. Serial No. 656,367.

The object of the present invention is to provide a novel form of circuit closing device for automobiles and more particularly for use in connection with the driver's seat.

5 The invention is satisfactorily illustrated in the accompanying drawing, but the important instrumentalities thereof may be varied, and so it is to be understood that the invention is not limited to the specific details shown and described, as long as they are within the scope of the claim.

10 Figure 1 represents a partial elevation and a partial vertical section of an auto theft alarm embodying my invention, the 15 seat of the vehicle being in raised position.

15 Figure 2 represents a top plan view thereof omitting the seat.

20 Figures 3, 4 and 5 represent vertical sections showing certain members of the invention in different positions.

Figure 6 represents a portion of the top of a box employed showing a keyhole therein.

25 Similar numerals of reference indicate corresponding parts in the figures.

Referring to the drawings:—

1 designates the seat of an automobile or other vehicle which is suitably hinged to the frame 2 of the vehicle below the same admitting of the raising and lowering of said seat. To said frame is secured the box 3 which is located below said seat and adapted to have the bottom 4 of the latter when lowered to rest on the top 5 of said box, as most plainly shown in Figures 3 and 4.

30 To the bottom of the seat is secured the sleeve 6 which extends in vertical direction and is adapted to enter the seat and move with the same while being raised and lowered.

35 On the bottom 2 of the seat is the latch plate 7 which is pivoted at one end on the bottom of the seat and located adjacent to the sleeve 6, said plate being adapted when moved laterally in one direction to close the base of the opening 8 in said sleeve, as shown in Figures 1 and 3, and when moved in the other direction to uncover said opening as shown in dotted lines in Figure 1, and in 40 full lines Figure 4.

45 In the box 3 is the switch mechanism consisting of the rockers 9 on the ends of which are contact pieces 10 which are adapted to engage opposite contact pieces 11 which latter are supported on the standards 12 within the box. To said standards are secured

5 by the binding screws 12 the conductors 13 and 14 leading respectively to the battery 15 and the bell 16 in the vehicle.

10 The switch mechanism in the box is of conventional form and adapted when a circuit is formed or closed to ring the bell 16 and when the circuit is broken said bell is silent.

15 Within the box is the additional rocker or double ended lever 17 which is mounted on the axial shaft 18 so as to move therewith, it being noticed that the rockers are subjected to the action of the spring 19 of the switch mechanism, whereby the rockers 20 are returned to the position from which they are thrown.

25 To one limb of the rocker 17 is pivotally connected the post 20, the same rising therefrom in vertical direction and adapted to 30 pass upwardly through the opening 21 in the top 5 of the box 3 and at a certain time to enter the sleeve or socket 6, see Figure 4. In this position the seat 1 may be occupied by the driver without moving said plug and so 35 the switch mechanism remains inoperative. On the other limb of the rocker 17 is the seat or abutment 22 for the end portion of the key 23 which may be passed through the key hole or opening 24 in the top 5 of the 40 box and so engage said abutment to press down and so lower the limb of the rocker 17 that carries said abutment 22.

45 The operation is as follows:—

50 When the driver stops the vehicle and leaves the seat 1 he raises the latter and the sleeve 6 is stripped from the post 20. The latch plate 7 is then moved over the exposed end of the sleeve so as to cover the opening therein, as shown in Figure 1. The 55 driver lowers the seat when the stop plate 7 contacts with the top of the post 20, the latter being held up by the action of the spring 19, and as it bears against the latch plate 7 the seat is prevented from fully closing down, as in Figure 5, said spring being 60 sufficiently powerful for the purpose. The driver now leaves the vehicle to enter a store, apartment or otherwise.

65 Should an unauthorized person take possession of the vehicle and occupy the driver's seat his weight will overcome the spring 19 and so the seat lowers to full extent from that shown in Figure 5 to that shown in 70 Figure 3 when the post 20 is accordingly lowered. This shifts the rockers, as shown in Figure 1, the circuit then being formed 75

whereby the bell 16 rings and this attracts the attention of the owner if within reach, a traffic officer, policeman or others, and indicates that the vehicle is about to be stolen or stolen if run off, when it may be pursued for recovery and arrest of the occupant.

When the owner or proper party re-enters the vehicle, he raises the seat, throws back the latch plate, thus uncovering the opening 10 of the sleeve inserts the key 23 or any push rod through the opening 24 and engages it with the abutment 22 of the rocker 17 and presses down said abutment, thus shifting the switch mechanism raising the post 20 15 and breaking the circuit when the bell ceases to ring.

The seat is lowered and so the sleeve passes over the top of the post without operating the latter and the parts are again in normal 20 position, as shown in Figure 4.

The bell will be placed in the vehicle as inaccessible as possible to the thief, and otherwise guarded that it cannot be cut out or removed and otherwise tampered with. If 25 desired, a spring may be employed to raise the seat to a small extent when the owner of the vehicle leaves the seat, this being apparent, as in Figure 5.

Having thus described my invention what 30 I claim as new and desire to secure by Letters Patent, is:—

The combination of a fixed lower structure, forming the lower part of a conven-

tional vehicle seat, a double pole switch member therein, comprising a pair of rockers, having oppositely located forked terminals, oppositely located pairs of upper and lower contacts coacting with said terminals for making and breaking a circuit, a shaft for said rockers, a vertically disposed post 40 pivoted at its lower ends between said rockers to said switch member and having its upper end guided in the top of said lower structure, an upper normally horizontally disposed, conventional vehicle seat hinged to 45 the rear of said lower structure, a vertically disposed hollow sleeve in said hinged member adapted to align with said post when said upper seat member is down, a latch plate hinged to the bottom of said upper 50 seat member and adapted to close the bottom of the hole in said sleeve, when turned into alignment therewith and an abutment carried by and movable in unison with said switch member and located between said rockers on the side of said shaft opposite to said post, said abutment aligning with a hole in the top of the fixed lower seat structure and adapted to be depressed by the insertion of a key through said hole, when it 55 is desired to open the circuit, the closing of the circuit and the operation of a signalling device being effected when said post is in its lowermost position.

BALDINI SCHMITH.
